UNITED STATES PATENT OFFICE

WELDON O. HAMPTON AND ERMINE J. THOMPSON, OF CHICAGO, ILLINOIS, ASSIGNEES
TO THE DELTA STAR ELECTRIC CO., OF CHICAGO, ILLINOIS, A CORPORATION OF
ILLINOIS

SWITCH

Original application filed September 27, 1926, Serial No. 137,930, now Patent No. 1,711,229, dated April 30, 1928. Divided and this application filed August 22, 1928. Serial No. 301,242.

This application is a division of our co-pending application, Serial No. 137,930, filed September 27, 1926, now Patent 1,711,229 dated April 30, 1929.

5 Our invention relates to electrical switch mechanism and more particularly to a class of switches of our invention which we preferably term "horizontal-vertical switches".

10 In recent times the transmission of power having high voltages has become a reality and engineers are constantly striving to meet and improve the conditions surrounding the use of high voltage transmission lines. Obviously, the increase in voltages necessitated that the dimensions and striking distances of the switch parts keep pace therewith. This is particularly true of disconnect switches which are usually associated with the power lines in exposed condition.

15 20 Now in three-phase power lines, the disconnect switches are associated therewith in multiple or in banks of three switches, one for each line. It has been the practice in operating switches, especially those of the rotary insulator type, to move the switch blade of each switch in substantially one plane, either a horizontal or a vertical plane, as the case may be. When the switch is in an opened condition, its blade will naturally be in a proximate position to the terminals of the adjacent switch. Then, too, in a disconnect switch it is necessary to move the blade to a position at least as distant from the fixed terminal as the end of the pivot terminal associated with the blade.

25 30 In order to make this possible in a bank of three switches of the rotary insulator type, the central switch is usually separated on each side from the adjacent switches by a distance great enough to accommodate the full length of the switch blade. This results in such switches occupying considerable space and necessitating a relatively large mounting for each bank of three disconnect switches which is not a desirable feature in the switch art.

35 40 We propose to remedy the above undesirable condition by providing a switch of the rotary insulator type wherein the blade is adapted to be swung from one plane to another, such, for example, as from a horizon-

tal plane to a vertical plane. In our novel switch construction the blade is mounted in such a manner upon the hinge terminal that it is adapted when actuated to be swung from a plane parallel to the base to a plane substantially at right angles thereto. It will be evident that in a bank of switches embodying the features of our invention, the switches may be positioned closer together, thereby reducing the size of mounting necessary for the bank of switches and thus resulting in economy as far as space is concerned.

45 50 In accordance with the features of our invention, we provide a switch wherein the blade is mounted in such a manner upon a rotary insulator, that upon motion being imparted to the insulator the blade will be swung in an arcuate path from a plane parallel to the base of the switch to a plane at substantially right angles thereto. Moreover, when the blade is in an opened position, it will extend outwardly from the rotary insulator and hence will be farther from the fixed terminal than the terminal associated with the top of the rotary insulator.

55 60 65 We also propose to provide improved operating mechanism for the rotary insulator as well as an improved non-freezable support therefor, both of our invention. Incidentally, we contemplate the provision of self-aligning contacts adapted to cooperate with the switch blade in such a manner as to insure a good electrical connection therebetween.

70 75 80 Other objects and advantages of the present invention will more fully appear from the following detailed description taken in connection with the accompanying drawings which illustrate several embodiments thereof and in which

85 90 Fig. 1 is an elevation of a switch embodying the features of our invention;

95 Fig. 2 is an enlarged plan view of the self-aligning contact flat terminal shown in Fig. 1;

Fig. 3 is another enlarged view of the same stationary terminal as illustrated in Fig. 2;

Fig. 4 is an enlarged plan view of the mounting of the switch blade illustrated in Fig. 1, and

Fig. 5 is a sectional view taken on the line 100

5—5 of Fig. 4 illustrating the beveled gear mechanism for actuating the switch blade.

The switch as thus shown in Fig. 1 comprises a supporting beam 230 and a pair of spaced vertical insulators 231 and 232. The insulator 232 is attached to a base 233 secured to the support 230. Mounted upon the top of the insulator 232 is a contact terminal device designated generally by the reference character 235. This device includes an arcing horn 236. Connected to this device is an end of an electrical transmission line 237.

Reference may now be had to Figs. 2 and 3 wherein the construction of the contact terminal 235 is shown in detail. The terminal includes a pair of pivotally mounted contact blocks 240 to each of which is connected an electrical conductor 241. The blocks are adapted to cooperate with the switch blade 20 to establish an electrical connection. It should be noted at this time that the blocks are adapted to be spread apart in order to permit of the blade being placed intermediate them.

25 Associated with each of the blocks is a resilient element 242 which has an aperture 243 for accommodating a projection 244 integral with the outer face of the block. The projection 244 cooperates with the element 242 to support the block 240. That is to say, the sole support for the block is afforded by the resilient element 242. The blocks are at all times urged toward each other by the said pair of resilient elements. Positioned over the blocks 240 is a shield 245 for protecting the blocks from the natural elements.

Now the free ends of the electrical conductors 241, which may each comprise a substantially flat copper ribbon, are separated by a 40 terminal piece 246. The free ends of the conductors, as well as the associated end of the terminal piece 246, are all positioned intermediate the ends of the pair of resilient elements 242. Moreover, the conductors 241, the resilient elements 242, and the terminal piece 246, are all fastened to the top of the insulator 232 by means of a clamping plate 247 and a pair of bolts 248.

50 The resilient elements 242 are adapted to at all times urge the blocks 240 toward each other. Furthermore, when the free end of the switch blade is positioned intermediate the blocks the resilient elements serve to force the blocks into engagement with the switch blade to establish a good electrical connection therebetween. The blocks are permitted to rock freely upon their pivotal mountings and are thus enabled to accommodate themselves with facility to the surface of the free ends of the switch blades. In other words, the blocks are self-aligning and are thus capable of at all times tightly engaging the switch blades. Fastened to the terminal piece 246 by bolts 249 is a terminal lug 250 in

which the end of the electrical conductor 237 is fastened.

The lower end of the insulator 231 is equipped with a shaft portion 251 suitably journaled in a base piece 252 fastened to the beam support 230. The shaft portion 251 is equipped with suitable locking bolts 253 located below the beam 230. These bolts maintain the insulator in its vertical position and prevent the same from tilting. Also, the lower end of the shaft portion 251 is equipped with a polygonal-shaped portion 254 to which a suitable wrench or lever handle may be connected for the purpose of revolving the insulator 231.

Spaced from the insulator 231 is another vertical insulator 255 suitably fastened to the beam 230. The pair of insulators 231 and 255 cooperate to support a drive device designated generally by the reference character 256. This device, in addition to serving as a means for actuating the switch blade designated generally by the reference character 257, serves as a mounting for the switch blade.

We shall now describe in detail the mounting and drive mechanism 256 which is illustrated in Figs. 4 and 5. The construction 256 includes a casing or housing 258 which is positioned immediately over the insulator 231. The housing 258 has bolted thereto a supporting strip 259 secured to the top of the insulator 255. Bolted to the housing 258 is a lug 259' of an electrical transmission line 260. Positioned inside of the housing 258 and disposed in substantially a horizontal plane is a bevel gear 261 which is connected to the top of the insulator 231 by means of a plurality of dowel pins 262. This bevel gear 261 is at all times in mesh with a bevel gear 263 positioned in a plane disposed at an angle to that of the gear 261. The casing 258 is provided with an opening 264 in axial alignment with the gear 261. Also the gear 261 is equipped with an opening 265 in axial alignment with the opening 264. Positioned in the openings is a bearing member 266.

The member 266 is provided with a central aperture through which the shank of a bolt 268 extends. The lower end of the bolt 268 is threaded into the top of the insulator 231. Also positioned intermediate the head of the bolt 268 and the casing 258 are a plurality of washers 269.

The gear 263 is splined to a shaft 270 which extends through an opening 271 in the casing 258. The upper end of this shaft 270 is provided with a head portion 272 which has formed integral therewith a socket-like portion 273 for receiving an end of the switch blade 257. The socket portion 272 is preferably split as indicated at 274 and the split portions are adapted to be bolted together by means of a pair of bolts and nuts 275. The bolts and nuts 275 engage flanges 276 formed

- integral with the split socket member 273. The socket member 270 is positioned at an angle with respect to the shaft 270. The angle is substantially greater than a right angle.
- 5 The socket member 272 is preferably connected to the head portion 272 by a pair of spaced legs 273. The tubular switch blade 257 has an end positioned in the socket member 272. Secured to this end of the blade by 10 a telescoping plug 275 is an end of a copper ribbon conductor 278 having its other end connected to the line 260. This conductor 278 serves as a means for by-passing the current around the housing 258 to the switch arm 257.
- 15 Associated with the head portion 272 is a grease cup 278 by means of which a lubrication medium may be projected into the inside of the casing 258. That is to say, the grease cup 278 is adapted to furnish lubrication to the bearings associated with the shaft 270 in a manner which will now be described in detail. The upper end of the opening 271 in the casing 258 is flared and provided with a 20 beveled edge 280. Positioned intermediate this annular beveled edge 280 and the head piece 272 are a plurality of steel balls 281 which serve as anti-frictional elements. Also, it should be noted that the head portion 25 272 is equipped with an annular flange 282 which overlaps the part of the casing 258 associated with the beveled edge 280. The lower end of the opening 271 is also flared and equipped with a beveled edge 284. Positioned intermediate the annular beveled edge 284 and the gear 263 are a plurality of anti-frictional elements or steel balls 285 which serve as an anti-frictional bearing for the shaft 270. The lower end of the shaft 270 is 30 reduced as indicated at 286. This reduced portion 286 is adapted to have threaded thereon a castellated nut 287. Positioned intermediate the castellated nut 287 and the gear 263 is a thrust washer 288. The castellated nut 287 may be locked in place by the usual cotter pin 289 which extends through a suitable aperture in the threaded portion 286 of the shaft 270.
- 35 It should be noted that the socket member 273 is cut away, as indicated at 290 in order for it to be moved without interfering with the head of the bolt 268. Also, it should be observed that the casing 258 is provided with a grease cup 291 by means of which lubrication may be supplied to the bearing 266.
- 40 Now, as previously described, the switch blade 257 is attached to the socket portion 273 by means of the bolts and nuts 275. The free end of the switch blade 257 is flattened 45 as indicated at 295. This flattened portion is adapted to be moved intermediate the previously described self-aligning contact blocks 240. Also the blade 257, which is preferably a tubular construction, has fastened thereto an arcing horn 296 for cooperation

with the arcing horn 236 associated with the stationary insulator 232.

The operation of our invention above described is believed to be obvious from the detailed description when taken in connection with the accompanying illustrations in the drawings. It will be evident that although the rotary insulator 231 is disposed in a vertical position, a horizontal-vertical movement may be imparted to the switch blade 257 to move it into or out of engagement with the self-aligning contact block 240. In this form of our invention the horizontal-vertical movement is accomplished by associating with the upper end of the vertical insulator 231 a bevel gear drive for the switch blade 257.

In order to minimize the stresses and strains imposed upon the insulator 231 by the mounting and driving mechanism 256, we find it desirable to provide an auxiliary insulator 255 which is adapted to cooperate with the rotary insulator 231 in supporting the bevel gear mechanism 256. The steel balls 281 and 285 associated with the shaft 270 in the bevel gear drive, perform two functions. One of these functions is to provide an anti-frictional support for the shaft 270 and the other function is to grind away any corrosive matter that might accumulate at the bearings of the shaft.

Furthermore, it should be observed that the device 256 may be disassembled with facility for the purposes of repair or the replacement of parts. Although the gear mechanism is associated with the upper end of the rotary insulator 231, the means for actuating the insulator 231 is associated with the base or beam 230. This will result in the entire insulator 231 being simultaneously actuated with the blade 257 when it is desired to move the same into or out of engagement with the cooperating self-aligning contact blocks 240 of the contact device 235.

Now we desire it understood that although we have described in detail an embodiment of our invention, the invention is not to be limited thereby, but only insofar as defined by the scope and spirit of the appended claims.

We claim:

1. In a switch, a base, a fixed insulator mounted thereon, a rotary insulator spaced from the fixed insulator and mounted on the base, a contact terminal associated with the fixed insulator, a switch blade associated with the rotary insulator and cooperable with the contact terminal, and a rotary gear connection between the top of the rotary insulator and the said blade for swinging the blade, said connection including a driven gear with its axis at an angle other than a right angle to the axis of the blade and with which the blade moves as a unit, whereby the blade is swung in a non-planar path.
2. In a switch, a base, a fixed insulator mounted thereon, a rotary insulator spaced

from the fixed insulator and mounted on the base, a contact terminal associated with the fixed insulator, a switch blade associated with the rotary insulator and cooperable with the contact terminal, a rotary gear connection between the top of the rotary insulator and the said blade, said connection including a driven gear the axis of which is at an obtuse angle to the axis of the switch blade and with which the blade is connected to move as a unit, the axis of said blade being disposed substantially parallel to the plane of the base when in engagement with the terminal and at an angle to the plane of the base when it is in an open position, and means for operating the insulator to rotate the driven gear and thereby move the blade in a substantially conical path into and out of engagement with the contact terminal.

20 3. In a switch, a base, a fixed insulator mounted thereon, a rotary insulator spaced from the fixed insulator and mounted on the base, a contact terminal associated with the fixed insulator, a switch blade associated with the rotary insulator and cooperable with the contact terminal, a gear connection between the top of the rotary insulator and the said blade, said connection including a driven gear with its axis of rotation at an angle other than a right angle with the axis of the blade and with which the blade is connected to move as a unit, and means associated with the lower end of the rotary insulator for operating the insulator and gearing to move the blade in a substantially conical path into and out of engagement with the contact terminal.

40 4. In a switch, a base, a fixed insulator mounted thereon, a rotary insulator spaced from the fixed insulator and mounted on the base, a contact terminal associated with the fixed insulator, a switch blade associated with the rotary insulator and cooperable with the contact terminal, means for moving the blade in a conical path laterally and away from the base to open the switch, said means including the rotary insulator and a gear connection between the top of the rotary insulator and the said blade, said gear connection including a bevel gear connected to the top of the rotary insulator, and a second bevel gear in mesh with the said first gear connected to the switch blade, the axis of the two gears intersecting at an angle other than a right angle.

55 5. In a switch, a base, a fixed insulator mounted thereon, a rotary insulator spaced from the fixed insulator and mounted on the base, a contact terminal associated with the fixed insulator, a switch blade associated with the rotary insulator and cooperable with the contact terminal, a gear connection between the top of the rotary insulator and the said blade, said gear connection including a first bevel gear connected to the top of the rotary insulator, a second bevel gear in mesh with said first gear, said blade being connected to

the second bevel gear with its axis at an angle to other than a right angle to the axis of the gear, a shaft upon which the second gear is mounted, a non-freezing rotary bearing support for said shaft, and a connection between said shaft and the blade, said bearing including a plurality of anti-frictional elements, and means associated with the lower end of the rotary insulator for operating the same to move the blade in a substantially conical path into and out of engagement with the contact terminal.

6. An outdoor switch comprising a supporting base, two stationary insulators mounted on said base in spaced relationship, a switch contact mounted on one of the insulators, a switch blade, and means for moving the blade out of engagement with the contact in a direction extending first substantially laterally of the base and at right angles to the plane of the supporting insulators and thereafter in a direction extending substantially vertically of the base to increase the striking distance between the blade and both the base and the movable contact, said means including a movable actuating insulator supported by said base and an actuating connection between the free end of said movable insulator and the blade.

7. An outdoor switch comprising a supporting base, two stationary insulators mounted on said base in spaced relationship, a switch contact mounted on one of the insulators, a switch blade, and means for moving the blade out of engagement with the contact in a direction extending first substantially laterally of the base and at right angles to the plane of the axes of the supporting insulators and thereafter in a direction extending substantially vertically of the base to increase the striking distance between the blade and both the base and the movable contact, said means including a movable actuating insulator supported by said base and an actuating connection between the free end of said movable insulator and the blade, said movable insulator being disposed between said stationary insulators and adjacent one of them.

8. An outdoor switch comprising a supporting base, two stationary insulators mounted on said base in spaced relationship, a switch contact mounted on one of the insulators, a switch blade, means for moving the blade out of engagement with the contact in a direction extending first substantially laterally of the base and at right angles to the plane of the supporting insulators and thereafter in a direction extending substantially vertically of the base to increase the striking distance between the blade and both the base and the movable contact, said means including a movable actuating insulator supported by said base and an actuating connection between the free end of said movable insulator and the blade, said movable insulator being

disposed between said stationary insulators and adjacent one of them, and a bracing connection between the top of the movable insulator and said adjacent stationary insulator.

5 9. A switch comprising a supporting base, a movable switch member having a generally horizontal closed position, means for swinging said switch member in a path extending first substantially laterally of the supporting base and thereafter extending substantially upwardly to the open position, said means including a stationary and a movable insulator both mounted upon said base and bracing means between the insulators, and means 10 contacting with the movable switch member in a generally horizontal closed position for completing a circuit therethrough.

15 In witness whereof, we hereunto subscribe our names this 16th day of August, 1928.
